UNITED STATES PATENT OFFICE.

JOHN F. BURNS, OF ST. LOUIS, MISSOURI.

STEAM-TRAP.

SPECIFICATION forming part of Letters Patent No. 781,329, dated January 31, 1905.

Application filed August 22, 1904. Serial No. 221,720.

To all whom it may concern:

Be it known that I, JOHN F. BURNS, a citizen of the United States, and a resident of St. Louis, Missouri, have invented a certain new and useful Telltale Steam-Trap, of which the following is a specification containing a full, clear, and exact description, reference being had to the accompanying drawing, forming a part hereof.

My invention relates to telltale steam-traps; and it consists of the novel features herein shown, described, and claimed.

In the drawing the figure is a central vertical section longitudinally of the trap.

Referring to the drawing in detail, the trap consists of a suitable casting 1, having a removable cap 2 and a partition-wall 3 arranged to form the receiving-chamber 4 and the blow-off chamber 5. The cap-plate 2 is elevated at one end to form the dome 6, and the inlet-pipe 7 is tapped into this dome 6 and communicates with the chamber 4. The outlet-pipe 8 is tapped through the plate 2 into the chamber 5. A petcock 9 is tapped into the plate 2 to let air out of the chamber 4, and a similar petcock 10 is tapped into the plate 2 to let air out of the chamber 5.

The automatic valve-seat casting 11 is tapped into the partition-wall 3, the valve-seat 12 in said casting being funnel-shaped, with its large end toward the chamber 4. A pivot 13 is mounted horizontally in the chamber 4, one end of the pivot being near the transverse center of the chamber and the other end of the pivot being secured to the wall. A lever 14 is mounted upon the pivot, said lever being normally slightly inclined from a vertical position. An arm 15 extends from the upper end of the lever to a position below the dome 6, and a float 16 is secured to the free end of the arm. A valve-stem 17 is pivotally connected to the lower end of the lever 14, and the valve 18 is fixed upon the end of the stem 17 in position to engage the seat 12. A guide-pin 19 extends from the point of the valve 18 through the valve-seat casting 11, so that when the valve 12 moves away from the seat it will be supported by the guide-pin 19. The valve 12 is operated to and from its seat by the raising and lower-

ing of the float 16. The valve-operating stem 20 is mounted in position to operate through the plate 2, and the arm 21 extends from the upper end of the lever 14 in position to be engaged by the stem of the valve 20, so that if the valve 12 sticks in its seat it may be withdrawn by screwing down the valve 20 upon the arm 21. A valve-supporting arm 22 extends from the lower end of the lever 14 under the valve-stem 17, so as to support the valve-stem when the valve is unseated beyond the limits of the guide-pin 19, there being fingers 23 extending upwardly from the end of the arm 22 beside the stem 17. A valve-seat casting 24 is tapped through the partition-wall 3 near the bottoms of the chambers, and a valve-seat 25 is formed in the casting upon the side toward the chamber 5. The valve-stem 26 is mounted through the wall of the chamber 5, and the valve 27, carried by the valve-stem, is in position to engage the valve-seat 25.

The inlet-pipe 7 may be attached to any device from which it is desired to draw the condensation, and the water of condensation will pass through the pipe 7 into the chamber 4.

The valve 27 is normally closed, and the weight of the float 16 holds the valve 12 normally closed. As the water rises in the chamber 4 to a point above the valve 12 the float 16 will operate the lever 14 and unseat the valve 12, and the steam-pressure will force the water through the casting 11 into the chamber 5 and outwardly through the pipe 8. When the float lowers by lowering the level of the water, the valve will again be seated until the water rises. If the passage through the casting 11 becomes clogged and the chamber 4 fills with water, the valve 27 is manually opened, and the steam-pressure will blow the water out of the chamber 4 through the chamber 5 into the pipe 8, and the reaction will unseat the valve 12. This operation of blowing the water out through the valve-casting 24 will clean all the dirt out of the trap. A water-glass 28 is mounted in position to show the height of the water within the trap.

Thus I have produced a telltale steam-trap—that is, one the condition of which may readily be ascertained from the outside with-

out taking the trap to pieces. When the air-valve 9 is open, if steam is discharged it indicates that the trap is in working order. If water is discharged, it indicates that the valve 12 is out of order either by sticking or by being clogged.

The water-glass 28 will be nearly filled with water when the trap is in working order, and by watching the water-glass the alternate opening and closing of the valve 12 may be timed.

By the various manipulations described the trap may be cleaned and operated indefinitely without removing the cap-plate 2 or any other 15 part.

I claim—

1. In a telltale steam-trap: a suitable casting having a partition and forming a receiving-chamber, there being valve-openings through 20 said partition, one near the bottom and one near the center; a valve-stem extending through the blow-off chamber; a valve upon the end of the valve-stem for closing the lower opening in the partition; a pivot in the receiving-chamber; a lever mounted upon the pivot; a float upon one end of the lever; a valve at the other end of the lever and closing the upper opening in the partition; substantially as specified.

2. In a telltale steam-trap: a suitable cast-

ing having a partition and forming a receiving-chamber, there being valve-openings through 30 said partition, one near the bottom and one near the center; a valve-stem extending through the blow-off chamber; a valve upon the end of the valve-stem for closing the lower opening in the partition; a pivot in the receiving-chamber; a lever mounted upon the pivot; a float upon one end of the lever; a valve at the other end of the lever and closing the upper opening 35 in the partition; and means for manually unseating the float-controlled valve; substantially as specified.

3. In a telltale steam-trap: a receiving-chamber; a blow-off chamber; a lower passage leading from the receiving-chamber to the 40 blow-off chamber; a valve for controlling said lower passage; an upper passage leading from the receiving-chamber to the blow-off chamber; a float-valve controlling said upper passage; and means for manually unseating the 45 float-valve; substantially as specified.

In testimony whereof I have signed my name to this specification in presence of two subscribing witnesses.

JOHN F. BURNS.
